UNITED STATES PATENT OFFICE.

WALTON HARRISON, OF BROOKLYN, NEW YORK

APPARATUS FOR TRANSMITTING SOUNDS.

1,150,267.

Specification of Letters Patent. Patented Aug. 17, 1915.

Application filed March 16, 1908. Serial No. 421,532.

To all whom it may concern:

Be it known that I, WALTON HARRISON, a citizen of the United States, residing in Brooklyn, in the county of Kings and State of New York, have invented a certain new and useful Apparatus for Transmitting Sounds, of which the following is a full, clear, and exact description.

My invention relates to the electrical 10 transmission of sounds by aid of powerful currents suitable for wireless telephony, and for wire telephones having multiple receivers, loud speaking receivers, or receivers used for long distance transmission.

15 My invention contemplates the use of an arc exposed to the direct action of sound waves, my special purpose being to increase the sensitiveness of the arc by guiding the sound waves against, into and through certain definite portions thereof, and also against, into and through certain definite portions of the electrodes associated with said arc.

20 My invention further embraces a provision for amplifying proportionately any current variations made by the action of sound waves upon the arc, by causing the light from the arc, and particularly the ultra-violet rays of said light, to react upon the arc 25 and quantitatively increase and diminish its resistance so as to assist the direct action of the sound waves in controlling said resistance. While my invention is intended primarily for the transmission of articulate 30 speech and other vocal sounds, and also instrumental music, it may be used in a variety of other relations.

35 My invention is used in connection with a large variety of arcs, including the ordinary lighting arc, the flaming arc, the Simon speaking arc, the Duddel singing arc, and the miscellaneous arcs used for the transmission of speech or other vocal sounds, either in wireless telephony or over lines.

40 In order that my invention may be readily understood I will first call attention to a few facts not generally known concerning the nature and action of the electric arc. As has been heretofore pointed out (see 45 "The Electric Arc", by Ayrton, page 393), the fundamental source of heat in the arc is not the positive crater, but is a thin film of carbon vapor covering this crater. This film has a very high ohmic resistance as 50 compared with other portions of the arc, and the vapor comprising it is, of course, unconfined. In 1894, Trotter made the dis-

covery (see "The Electric Arc", ante page 69), that the arc has, in the proximate center of the positive crater and separated 50 slightly therefrom, a portion which he designated as the "bright spot". This bright spot is a region of exceptional brilliancy, and has an area of about one-fourth that of the crater. It is most noticeable, according 65 to Trotter, in what he designated in the nomenclature of that day, as the "humming" arc, though Ayrton expresses the belief that it is found in practically all other arcs. Photometric and stroboscopic tests by 70 Trotter showed that it had usually a definite shape—which, however, was not always the same and was sometimes asymmetrical. These tests showed further that it had a rapid rotary movement, ranging from 100 75 to 450 revolutions per second, and that its direction of rotation was sometimes reversed. Also (and here is a significant point) that the tone made by the arc in 80 humming corresponded with the frequency of the revolutions of the bright spot, and when these exceeded 450 per second, the sound of the arc changed from a hum to a hiss. A telephonic receiver connected with the circuit emitted a tone corresponding to 85 the acoustical tone of the arc. From this data it is easy to see a direct and positive relation existing between those rotational movements and the amperage of the current supporting the arc. 90

I have made the discovery that, if Trotter's bright spot be disturbed or shaken by the aid of a force applied to it extraneously, all other portions of the arc remaining as far as practicable undisturbed, the amperage of the entire current supporting the arc 95 is varied enormously, yet substantially in proportion to the disturbance of the bright spot. I have also discovered that in the antipodal portion of the arc, near the negative electrode, there is another region which behaves much like the bright spot, at least to the extent of controlling the current when disturbed, but in a lesser degree. Moreover, I have found it to be practicable, by 100 the use of a mouthpiece having at its bottom an opening of the order of a pinhole, to concentrate sound waves directly upon the bright spot, or upon its unnamed companion, at the other end of the arc, so as to impress 105 upon the current variations greater in degree and more sharply defined than variations made by disturbing any or all other parts of the arc. I have also made the dis-

covery that if the light, and especially the ultra-violet rays, emitted by the arc be reflected back and focused upon the arc, variations in the condition of the latter are amplified or exaggerated so that corresponding variations, greater in degree, are made in the current, and these assist the initial current variations.

For the sake of clearness I show only a few embodiments of my invention, but it will be understood that the same purposes can be attained otherwise, yet in accordance with the spirit and intendment of my invention.

Reference is to be made to the accompanying drawings forming a part of this specification, and in which like letters indicate like parts.

Figure 1 is a view partly in elevation and partly diagrammatic, showing a circuit including a flaming arc, and means for directing sound waves through a minute opening toward the most sensitive part of the arc for the purpose of varying the resistance of the arc, and thus controlling the line current so as to transmit the sounds; this view also showing the arc as surrounded by a spherical globe of glass, for reflecting the light of the arc and focusing the same for the purpose of affecting the current; Fig. 2 is a diagram showing my invention as applied to a singing arc as used for wireless telephony, this arc employing a solid metallic negative electrode and a water-cooled metallic positive electrode, through the crater of which the sound waves reach the most sensitive portion of the arc; Fig. 3 is a detail of Fig. 2, showing how the mouthpiece extends into the water-cooled positive electrode and has a minute opening which terminates flush with the positive crater of the arc; Fig. 4 is a view showing in section a pair of electrodes of a form slightly different from those shown in Fig. 2, the minute opening in this instance having its axis nearly tangential to the positive crater, and in line with a certain portion of the arc selected because of its extreme sensitiveness, as hereinafter described; and Fig. 5 shows another pair of electrodes supporting an arc, the sound waves in this instance being directed into the arc through a minute opening in the negative electrode.

Mounted upon a support 1 of insulating material is a base 2 provided with a tubular holder 3, in which is a stem 4 adjustable by aid of a screw 5. The stem 4 carries a ring 6 provided with an adjusting screw 7. A mouthpiece 8 is provided with a rear wall 9 having a minute opening 10, preferably about $\frac{1}{2}$ of an inch in diameter.

Extending upwardly from a base 11 is a stem 12, supporting brackets 13, 14, insulated therefrom by aid of sleeves 15, 16 of non-conducting material. Adjusting screws 17, 18 are used for raising and lowering the

brackets 13, 14. Mounted upon the bracket 14 is a binding post 19, from which a wire leads to a battery 21, or equivalent source of electricity. From the battery a wire 22 leads to the primary winding 23 of a transformer 24, and from the primary winding a wire 25 leads to a binding post 26 upon the bracket 13. The brackets 13, 14 carry screws 27, 28, which secure carbon electrodes 29, 30 in suitable position, and permit their adjustment from time to time. An arc 31 is formed between the electrodes, the upper end of the arc springing from the crater 32 of the positive carbon, and the lower end of the arc resting upon the tip of the negative carbon. The portion of the arc designated by Ayrton and Trotter as the "bright spot" is indicated by an appropriate legend. This bright spot is the most sensitive portion of the arc, for purposes of controlling the current by the acoustical action of sound waves. At 34 is a glass globe supported upon the mouthpiece 8 and provided with ventilation holes 35. This globe is not essential for all purposes, and may be discarded whenever desired. Its purpose is to reflect the light, and especially the ultra-violet rays, back upon the arc and thus affect its state of ionization. By doing this, the light increases the sensitiveness of the arc, and exaggerates and improves its control over the current. The secondary winding 36 of the transformer is connected with line wires 37, 38, the latter being connected by wires 39, 40 with telephonic receivers 41, the latter being in parallel with each other. There may be several hundred or even several thousand of these receivers all controlled by a single arc. Loud speaking receivers, long distance receivers, or even speaking arc receivers may be substituted. Sounds of any kind, including articulate speech, being made in the mouthpiece, the sound waves pass through the opening 10 and cause the bright spot to vibrate. This varies the resistance of the arc, and impresses upon the current characteristics analogous to sound waves, thus reproducing the sounds by aid of the receivers. The current variations are amplified by the action of the ultra-violet light, as above described.

The chemical and physical composition of the bright spot, its temperature, and its exact chemical and physical relations to the film of vapor in immediate contact with the positive crater, as well as the cause of its sensitiveness, are subjects upon which volumes of speculative literature could be written. In order to explain the construction, and action of my invention, however, there appears to be no necessity for pursuing this phase of the subject. Suffice it to say, in general terms, that the arc has an exceptionally sensitive region easily located by reference to the bright spot, but which may

be located also by reference to the positive crater and the vapor film; that the region in question happens to be of small area and readily accessible from the outside; that it approximates the hottest portion, and that by concentrating the sound waves into the form of a column of very small diaméter, they can be directed into this region. The shape of the positive crater and of the electrodes may assist this object. In practice, I simply direct the sound waves into the proximate center of the positive crater and thus into the hottest portion of the arc. The globe 34 increases the variations of the current, no matter how they are initially produced. This action is due to the fact that varying quantities of the light rays, and especially the ultra-violet rays, when sent by reflection and diffraction back into the arc, vary its state of ionization. Suppose, for instance, that a particular sound wave or a function thereof by its direct acoustical action causes a momentary increase in the current. The light becomes momentarily brighter, the number of rays emitted from and then concentrated upon the arc is correspondingly increased, and the ionic activity of the arc is enhanced, thereby decreasing its resistance and further increasing the current. When, however, the direct acoustical action happens to diminish the current, it also diminishes the number of rays and lessens the ionic activity, thereby increasing the resistance of the arc and, consequently cutting down the current. As ordinary glass is opaque to ultra-violet rays, it answers very well as a material for the globe, which need not necessarily be made opaque to ordinary light.

In the arrangement shown in Fig. 2, two choking coils 42, 43 are connected with direct current mains 44, 45, and from the choking coil 42 a wire 46 leads to a copper cylinder 47, filled with water 48, and supporting a globe 49 of glass opaque to ultra-violet rays. A mouthpiece 50 has a pinhole opening 51, preferably about $\frac{1}{2}$ of an inch in diameter, immediately over the bright spot, and in close proximity thereto. This opening is in axial alinement with the bright spot, so as to readily direct sound waves into, through and against the same. The water-cooled cylinder is the positive electrode. The negative electrode 52 is a solid metallic rod, having its upper end hemispherical. It is connected by a wire 53 with the choking coil 43. A wire 54 leads from the positive electrode to a condenser 55, which is connected by a wire 56 with the primary winding 57, which is connected by a wire 58 with the negative electrode 52, and is in inductive relation with a secondary winding 59, the latter being directly connected with an aerial 60 and grounded at 61.

The capacity of the condenser 55 and the

inductance of the primary winding 57 are apportioned with a view to producing a singing arc and thus setting up sustained oscillation for purposes of wireless telephony. The positive electrode is provided with a concave hemispherical bottom 62 to which the reduced end of the mouthpiece is secured.

When the arc is started oscillations are set up in the manner heretofore known. Words being now spoken into the mouthpiece or other sounds conveyed thereto, the sound waves are concentrated and pass through the pinhole opening and into the sensitive region of the arc, agitating the bright spot and the portions of the arc in immediate proximity thereto. In doing this the sound waves also pass directly into the hottest part of the positive crater and through the thin film of vapor in immediate contact with said crater. Moreover, it is through the center of this film that the sound waves pass when they are directed into the geometrical axis of the arc, as indicated in Figs. 2, 3, 4 and 5. The sound waves thus disturb the film and the center of the light spot, and furthermore, have more or less tendency to disturb the temperature of the crater. All of these effects contribute to a common end, to wit, the variation of the resistance of the arc in accordance with sound waves. This much being granted, the rest of the action is substantially the same as already known and heretofore employed for purposes of wireless telephony.

In Fig. 4 the water-cooled cylinder is shown at 63, the mouthpiece at 64, and the pinhole opening at 65. In this device the axis of the opening 65 passes tangentially into the crater and obliquely against the bright spot, for the purpose of displacing the same, together with the center of the film of vapor, in a direction crossing the general axis of the arc. Otherwise the action is the same as in the device shown in Figs. 1 and 2.

In Fig. 5, the copper cylinder is shown at 66, the water for cooling the same at 67, and the copper bottom for the cylinder at 68. This copper bottom is provided with a protuberance 69, for centering the arc and steadyng the bright spot. The mouthpiece is shown at 70, and is made of copper having an integral upturned portion 50, which is made comparatively thick in order to withstand the heat, and is provided with a pinhole opening 71 which is directed toward the bright spot, and is in axial alinement with the center thereof. As the arc in a device of this kind can be made very short, the pinhole opening is brought into close proximity to the bright spot, the center of the film and the center of the positive crater, although in this instance, as in the others, the upper electrode is positive and the lower one negative. The glass globe,

being removable, can be used in connection with any of the arcs above described, or discarded whenever desired.

I make no attempt to illustrate the film 5 of vapor intermediate the bright spot and the positive crater.

The gases and vapors comprising the body 10 of the arc together constitute a transient conductor which, being heated by the passage of electricity through it, is in a state of intense ionic activity, as is also the air to which the arc is exposed. My apparatus, therefore, acting in conjunction with sound waves, makes alterations in the state of 15 ionization of both the transient conductor and the air, thereby affecting the resistance of the transient conductor. What is true of the arc is in general true of any other transient conductor which, when 20 heated by the passage of electricity through it, becomes ionized or has the effect of ionizing the air or other free medium whereby it is surrounded.

I use the expression "transient conductor" in a broad sense, meaning thereby to include a gas, a vapor, or a mixture of gases and vapors, capable of serving temporarily as a conductor when heated, or otherwise directly acted upon, by electricity. I also 30 use the term "aeriform body" in a broad sense, meaning to include thereby any gas, vapor or other practically weightless body of air-like form, whether free, confined, or partially confined.

35 Having thus described my invention, I claim as new and desire to secure by Letters Patent:

1. The combination of a circuit including an electric discharge crossing a gap and 40 having within said gap a portion particularly sensitive to ionization, and means for selectively subjecting said portion to the action of a varying ionizing force.

2. The combination of a circuit including 45 an electric discharge having a predetermined portion particularly sensitive to ionization, and means for selectively applying to said sensitive portion an ionizing force having variations analogous to sound waves.

50 3. The combination of a circuit including an electric discharge having a predetermined portion particularly sensitive to ionization, and means for selectively applying to said sensitive portion an ionizing force extraneous to said electric discharge and impressed with variations analogous to sound waves.

4. The combination of a circuit including 55 an arc and a pair of electrodes between which said arc is formed, said arc having a portion particularly sensitive to sound waves, one of said electrodes being provided with means for cooling it in order to in-

crease the sensitiveness of said portion of said arc, and means for selectively directing 65 sound waves against said portion.

5. The combination of an electric circuit including an arc and a hollow electrode, forming a terminal for said arc, a mouthpiece provided with a portion extending toward said arc and connected with said electrode, and a quantity of liquid located within 70 said hollow electrode for the purpose of cooling both said electrode and said portion of said mouthpiece. 75

6. The combination of a circuit including an arc, a mouthpiece provided with a portion extending into close proximity to said arc for the purpose of subjecting said arc to resistance variations analogous to sound 80 waves, and cooling mechanism connected with said portion of said mouthpiece for the purpose of cooling the same. 85

7. The combination of a circuit including an arc, a telephonic receiver controllable by 85 said circuit, mechanism including a mouthpiece directed toward said arc for exposing the latter to sound waves, and means for cooling a portion of said mouthpiece in close proximity to said arc. 90

8. The combination of a circuit including an arc provided with a particularly sensitive portion having a high temperature, a mouthpiece having a portion extending close to 95 said sensitive portion of said arc, and having a minute opening adjacent to said sensitive portion of said arc, and means for preventing undue heating of said portion of said mouthpiece.

9. The combination of a circuit including 100 a gap across which electricity flows, said gap with said electricity flowing across it having a portion particularly sensitive to disturbances extraneous to said circuit, and means extraneous to said circuit and acting 105 conjointly with sound waves for selectively disturbing said portion.

10. The combination of a circuit including 110 a gap across which electricity flows, said circuit being sensitive to ultra-violet light thrown into said gap, and means for directing into said gap sound-controlled quantities of ultra-violet light.

11. The combination of a circuit including 115 a gap across which electricity flows, said circuit being sensitive to ultra-violet light, and means for exposing said gap to variations, analogous to sound waves, in the quantity of ultra-violet light thrown thereupon.

In testimony whereof I have signed my 120 name to this specification in the presence of two subscribing witnesses.

WALTON HARRISON.
